UNITED STATES PATENT OFFICE.

OSCAR GASSETT, OF BOSTON, MASSACHUSETTS, ASSIGNOR TO THE UNION SWITCH AND SIGNAL COMPANY, OF PITTSBURG, PENNSYLVANIA.

RAILWAY ELECTRIC SIGNAL APPARATUS.

SPECIFICATION forming part of Letters Patent No. 267,978, dated November 21, 1882.

Application filed January 3, 1882. (No model.)

To all whom it may concern:

Be it known that I, OSCAR GASSETT, of Boston, county of Suffolk, State of Massachusetts, temporarily residing at Sewickley, county of 5 Allegheny, State of Pennsylvania, have invented or discovered a new and useful Improvement in Railway Electric Signal Apparatus; and I do hereby declare the following to be a full, clear, concise, and exact description there- 10 of, reference being had to the accompanying drawings, making a part of this specification, in which—like letters indicating like parts—

Figure 1 shows an electrical apparatus in connection with a diagrammatic view of a rail- 15 way-track, forming a part thereof, and the whole being illustrative of my present invention. Figs. 2 and 3 are detached views of a portion of the apparatus of Fig. 1, showing different portions of the armatures and locks 20 at different steps of the operations involved; and Figs. 4 and 5 are detached views, to an enlarged scale, of the upper ends of the armature-locks, illustrative of their action, and also of the circuit-contacts formed thereby.

25 My present invention relates more especially to an automatic system of electric signaling for single track roads. Such a single track is represented at $z z' z^2 z^3$. So much or such parts as are to be protected by signals are divided 30 into blocks of any desired length by means of insulating material inserted between the rail ends, as at $x x'$, in any of the ways known to the art, and a like insulation is made, as at x' , say, at or near the middle of the block, so as 35 to divide each block into two sections, $R R'$.

I have not deemed it necessary to show the signals, nor the mechanism employed between them and their actuating electro-magnets, since such mechanism of various forms and construc- 40 tions is already well known; but whatever signal be employed one is suitably arranged at or near each end of the block in such manner as to be actuated or shifted by the making and breaking of a circuit through electro-magnets 45 B and B' at or near opposite ends of the block. Each line of rails between insulated points has the usual electrical connections from rail end to rail end.

Batteries $a a^3$ are arranged one at or near

each outer end of the block, and their oppo- 50 site poles are connected electrically with the opposite rail-lines of the sections by wires 1 2 and 21 25, as shown. The wire coils of electro-magnet B connect at one end by wire 7 with battery a' , and thence by wire 13 with the 55 line of rails z^2 . The other end of the coil leads by line-wire 8 to binding-post s^4 . The coil of electro-magnet B' connects at one end by wire 14 with battery a^2 , and through it by wire 30 with rail-line z , and at its other end by wire 15 60 with binding-post s^5 . The rail-lines are connected at or near the middle of the block, the one z^2 by wire 12 with binding-post s^6 ; another, z^3 , by wire 22 with binding-post s^7 ; another, z , by wire 3 with binding-post s^7 , and the fourth, 65 z' , by wire 4 with binding-post s^6 .

At any suitable convenient point—say about the middle of the block—I arrange an electrical apparatus having three electro-magnets, A , A^3 , and D . The electro-magnets A , A^3 have 70 armature-levers A' , A^2 , respectively, each pivoted at one end to an insulated base, and swinging at the opposite end within a limited range, which, with A' , is fixed by adjustable stops $c e$, and with A^2 by like adjustable stops, 75 $c' e'$, such stops being supported by or from fixed posts $d d'$. The relay-magnet D has an armature, D' , which is attached to a bent armature-lever, D^2 , pivoted at d^2 , and provided with adjustable stops $d^3 d^4$. The extreme end 80 of the armature-lever D^2 carries a metallic locking-bar, c^5 , which is insulated as regards the lever by insulating material c^4 , Figs. 4 and 5, and such locking-bar has at its ends projecting lugs $c^2 c^3$, which operate as contact-points, 85 as hereinafter explained. These lugs, when the armature-lever D^2 is depressed, come outside the free ends of the armature-levers A' , A^2 , as shown in Figs. 3 to 5, and when D^2 is raised the lugs clear the ends of A' , A^2 , as 90 shown in Figs. 1 and 2. The free end of the armature-lever A' has a contact-button, 28, which is insulated by suitable material, 50, from its lever, and a like button, 27, is similarly arranged on the armature-lever A^2 . The button 95 28 is connected by wire 29 with binding-post s^3 , and button 27 has a like wire connection, 26, with wire 17, which leads to one pole of re-

lay-magnet D. A branch wire, 18, leads from this connection to the fixed post d' . The armature-lever A^2 is connected by wire 19 with binding-post s^3 . The armature-lever A' has like connections by wire 10 with binding-post s^2 . The opposite pole of D is connected by wire 16 with post s^5 . Wires 5 and 6 connect the opposite poles of A with posts s^7 s^8 , and wires 23 and 24 connect the opposite poles of A^3 with posts s^1 s^2 . Posts s and s^2 are connected by wire 11, and posts s^3 and s^7 by wire 20. Retractile springs s^8 , s^9 , and s^{10} secure the return motions of the armatures. The apparatus being thus connected, its condition as regards contacts and circuits, when rail-circuits are unbroken and no train or part of a train is on the section or block, will be substantially as represented in Fig. 1. A closed circuit exists through the signal-actuating magnets B' B , so as to hold the signals at "safety." Thus, beginning at the right of Fig. 1, and from battery a , a continuously-closed circuit exists by wires 1 and 2, rails z z' , and wires 3, 4, 5, and 6, through the coil of electro-magnet A, so as to excite the same and attract or draw over its armature-lever A' , so as to make electrical contact at or near its free end with the contact-screw c , and this closes a circuit from the battery a' at the other end of the section through the signaling-magnet B at that end, by wires 7 8 9, post d , contact c , armature-lever A' , wires 10, 11, and 12, and rails z^2 and wire 13. This has the effect of exciting the electro-magnet B, so as to hold at "safety" the signal actuated thereby. The first circuit thus described—namely, that through battery a and electro-magnet A—I will designate "circuit No. 1," and the other circuit described—namely, that through battery a' and signaling-magnet B—may be called "circuit No. 2."

It may be explained here that the set-screw c acts both as a contact in closing circuit, as just stated, and also as a stop, as before stated, so as to prevent actual contact of the armature with the pole or poles of the magnet A. Also, the same is true of the set-screw c' . Also, at the same time the closed circuit through battery a^3 , at the left-hand end of the block, will keep the electro-magnet A^3 excited, so as to keep the armature-lever A^2 over against the contact c' . This circuit, which I will call "No. 3," is, by wires 21 and 25, rails z^2 z^3 , and wires 12, 22, 23, and 24, through the coils of A^3 . The contact at c' thus made closes another circuit, which I will call "No. 4," which circuit passes through the battery a^2 , and by wire 14 through the signaling-magnet B' , and thence follows wires 15 and 16 through the relay-magnet D, thence by wires 17 and 18, post d' , contact c' , armature-lever A^2 , wires 19, 20, and 3, to and along rail z and wire 30, back to the battery. This keeps the electro-magnet B' excited and holds its signal at "safety," and also excites the relay-magnet D, so as to attract its armature or pole-piece D' and hold the free end of the armature-lever D^2 in a raised position, so that the lugs c^2 c^3 will be held clear of

the free ends of the armature-levers A' A^2 . This represents the normal condition of the apparatus. Now, when a train approaches from the right in the direction of the arrow w its first effect is to short-circuit the circuit through battery a , or circuit No. 1, with the result of demagnetizing the magnet A and allow its armature A' , under the influence of the spring s^9 , to move over to the insulated stop e and break the contact c , as shown in Fig. 2. This breaks circuit No. 2, or the circuit through battery a' , which includes the electro-magnet B, lets the corresponding signal come to "danger" under the effect of a weight or spring, and thereby protects this train as against a train approaching on the same track from an opposite direction. As soon as the forward end of the train entering at w passes the insulated point x' between the two sections shown, it short-circuits the left-hand section of track, or circuit No. 3, so as to cut out the electro-magnet A^3 from the influence of its battery a^3 , and therefore allows its armature A^2 , under the influence of its spring s^8 , to break contact at c' and come over to the insulated stop e' , as shown in Fig. 3. This breaks the circuit No. 4, which includes the relay-magnet D and the signal B' , as a result of which the signal which is under the influence of B' gives the danger-signal and protects the rear of the train as against a following train, and the armature-lever D^2 will drop down, so that the two projecting lugs c^2 and c^3 will go outside the upper ends of the armature-levers A' and A^2 , as shown in Fig. 3. As soon as the rear of the train passes the point x' the circuit No. 1 through the rails z z' is restored, so as to excite the magnet A and attract its armature A' . This makes a contact by button 28, as shown in the right side of Fig. 4. When the train passes off the left-hand section it restores the circuit No. 3 through the track-rails z^2 z^3 , as the result of which the magnet A^3 is excited, so as to attract its armature A^2 and make contact by button 27, as shown at the left-hand side of Fig. 5. This produces a circuit from the battery a^2 by wire 14, magnet B' , wires 15 and 16, through magnet D, thence by wires 17 and 26 through the button 27, and by lug c^2 and bar c^5 to the lug c^3 , button 28, wires 29, 20, and 3, and rails z and wire 30, to the battery a^2 . This excites the magnet D, which attracts its armature D' , raises the armature-lever D^2 , so that the bar c^5 , with its lugs c^2 and c^3 , shall be carried up and clear of the armature-levers A^2 and A' , and the latter will then be free to move under the operation of their respective magnets to normal position, which positions will restore and preserve the circuits through B and B' and shift the signals to "safety" positions and hold them there till otherwise actuated by a train, or by a breaking of the circuit from accident or malice. This circuit through the bar c^5 , lugs c^2 c^3 , and buttons 27 and 28 may be designated as "circuit No. 5." Its office is to restore the apparatus to normal position. Thus it will be seen that a train running as described will to the extent

set forth be protected as against other trains, both in front and rear. If a train approaches from the left, as indicated by arrow w' , its first effect, as its forward end passes the insulating-point x at the left, will be to short-circuit the No. 3 circuit, or the circuit through battery a^3 . This will demagnetize the electro-magnet A^3 and release the armature-lever A^2 and break the contact at c' . Thus the circuit No. 4 through battery a^2 and magnets B' and D will be broken, and the signal at B' will go to "danger" under the influence of a weight or spring, as is usual in such apparatus, and the train will be protected as against a train coming in the opposite direction, or from the right. When the forward end of the train coming from the left passes the insulating-point x' it will short-circuit the circuit through battery a , or No. 1 circuit, with the result of demagnetizing the magnet A , so as to release the armature-lever A' , and by breaking the contact at c break the circuit No. 2 through battery a' and signaling-magnet B , whereby the corresponding signal will go to "danger" and protect the rear of the train as against trains following. As soon as the rear of the moving train leaves section R' the circuit will be restored through battery a^3 , with the result of exciting electro-magnet A^3 and drawing armature-lever A^2 over till contact-button 27 makes contact with lug c^2 . Also, as soon as the rear of the moving train passes off section R the circuit through battery a will be restored, electro-magnet A will be excited, and armature-lever A' will be drawn over till its button 28 will make contact with lug c^3 , Fig. 5. This completes circuit No. 5, with the result, as before, of raising the tail end of the armature-lever D^2 and restoring the apparatus to normal position.

The organization thus described is designed particularly for single-track roads, and it is arranged so as to work automatically with trains going in either direction, so as to protect such trains, both as against trains in front going in the opposite direction and trains following in the rear.

It will be observed that the maintenance normally of the signal-circuits Nos. 2 and 4 depends on the preservation of the track-circuits Nos. 1 and 3, and that each end track-

circuit governs the signaling-circuit at the opposite end. Also, the lugs c^2 c^3 , in connection with buttons 27 28, perform the function of circuit-closers, and other known suitable forms of circuit-closers may be substituted therefor.

As regards each of the armature-levers $A'A^2$, the armature-lever D^2 operates very much as an escapement or stop, preventing for a time the movement of one or the other of said armature-levers, and, considering now the armature-lever D^2 as an escapement-lever, it will be noticed that it is actuated by an electro-magnet, D , which at the moment of actuation is included in the same circuit as the signaling-magnet B' , and that the normal circuit of B' is closed or restored by the release of the escapement; or, in other words, by the release of the escapement or stop, both electro-magnets are thrown onto another circuit; and such feature of construction I believe to be new with myself, and I include the same herein without limitation as to the use to which it is put.

In a separate application filed herewith I have made provision for doing substantially the same work as is herein provided for without the use of a relay-magnet, as herein described, and the following claims are limited accordingly.

I claim herein as my invention—

1. A block signaling apparatus having in combination a normally-closed track-circuit at each end of the block, a signaling-circuit also at each end of the block, each such signaling-circuit being closed by the track-circuit at the opposite end of the block, and a fifth circuit extending through a relay-magnet for restoring the apparatus to normal condition, substantially as set forth.

2. Two electro-magnets included in the same battery-circuit, one of which operates a stop or escapement by which to throw both said electro-magnets into another circuit, substantially as set forth.

In testimony whereof I have hereunto set my hand.

OSCAR GASSETT.
